UNITED STATES PATENT OFFICE.

CAROLINE REBER, OF RED LODGE, MONTANA.

UNDERWEAR ATTACHMENT.

1,259,046.

Specification of Letters Patent. Patented Mar. 12, 1918.

Application filed May 29, 1917. Serial No. 171,702.

To all whom it may concern:

Be it known that I, CAROLINE REBER, a citizen of the United States of America, residing at Red Lodge, in the county of Carbon and State of Montana, have invented certain new and useful Improvements in Underwear Attachments, of which the following is a specification, reference being had therein to the accompanying drawing.

10 This invention relates to an underwear attachment and has for its object the production of a support for a sleeveless vest without shoulder straps from slipping down over the bust of the wearer and at the same 15 time doing away with the necessity of two straps passing over the shoulder when worn under a corset-cover or brassière.

Other objects and advantages of the present invention will appear throughout the 20 following specification and claim.

In the drawings:

Figure 1 is a perspective view of a portion of a corset-cover showing the sleeveless vest supported thereby.

25 Fig. 2 is a plan view of the inner portion of a corset-cover showing the manner of supporting the sleeveless vest.

Fig. 3 is a transverse section through the shoulder strap showing the manner of 30 securing the sleeveless vest thereto.

Fig. 4 is a plan view of a portion of the sleeveless vest showing the socket portion of the spring clasp secured thereto.

35 Fig. 5 is a plan view of one end of the supporting tape.

By referring to the drawings it will be

seen that 1 designates the shoulder strap of the corset-cover 2 over which the supporting tape or strip 3 passes. This tape or strip is stitched or otherwise secured to the front 40 portion of the sleeveless vest 4 upon or near the upper fold or seam 5. The tape 3 then passes over or around the front portion of the shoulder strap 1 and the ball portion 6 of the spring clasp which is carried by the 45 free end thereof interlocks with the socket portion 7 of the spring clasp carried by the same or fold 5.

By carefully considering Fig. 1 of the drawings it will be seen that the sleeveless 50 vest is adapted to pass under the arm of the wearer and that the tape will efficiently support the front portion thereof by encircling the shoulder strap 1 of the corset-cover 2.

It should be understood that the device 55 produced comprises a very simple structure of a minimum number of parts which will hang snugly upon the body of the wearer and will not pucker.

What is claimed is:—

As a new article of manufacture a sleeveless vest, a supporting tape secured at one end to said vest and adapted to pass around the shoulder strap of a corset-cover, a spring clasp secured to said tape and vest for detachably holding the free end of said tape in a closed position around the shoulder strap of a corset-cover. 65

In testimony whereof I hereunto affix my signature.

CAROLINE REBER.
